UNITED STATES PATENT OFFICE

HERBERT M. FRIENDLY, OF CHICAGO, ILLINOIS; MILTON S. FRIENDLY AND CENTRAL
REPUBLIC BANK & TRUST CO., EXECUTORS OF SAID HERBERT M. FRIENDLY,
DECEASED

APPARATUS FOR FAULT LOCATION ON ELECTRICAL CONDUCTORS

Application filed July 10, 1926. Serial No. 121,667.

An object of the present invention is to provide a type of fault locating apparatus of the so-called Wheatstone bridge general class, which is particularly adapted for use by telephone and telegraph wirechiefs, though it has other uses.

While elements of the present invention correspond to those of the so-called Wheatstone bridge, which is well known, the structure and organization of the present invention is distinctly different, looking towards rapidly executing tests and for obviating mathematical calculation or reference to formulæ in reducing the test observation date to the desired units.

Reference is made to my Patents No. 859,556 of July 9, 1907; No. 1,034,609 of August 6, 1912; No. 1,057,817 of April 1, 1913. In view of the said patents, it is thought that the principles, operation and general adaptations of the present invention will be clear from the descriptions to follow. The present invention employs certain basic principles disclosed in said patents. However, it involves mechanical and electrical modifications not disclosed therein.

A salient object of the present invention is the provision of means whereby the minimum of operations are required and the minimum of time in taking observation data is required; because in testing for faults, particularly on telephone and telegraph lines, time is an important factor in restoring service. Moreover, in instances, a time limit may be a determining factor in making the test. Again, due to a transitory fault condition, but a brief time may be allowed to take observations for data upon which the location of the fault can be determined.

In locating certain kinds of faults in local telephone exchange operation it is necessary to have the two conductors of the line under test connected together conductively at the distant end; at least beyond the fault with reference to the location of the tester. The tester, under such condition, must depend upon the subscriber of the line under test to effect this connecting together conductively of the sides of the line at the time of making the test. Obviously, the subscriber should

not be annoyed by knowingly aiding in the conducting of these tests. The present invention enables the wirechief to call a subscriber whose line he wishes to have closed at the subscriber station, and after a response has been obtained from the subscriber (wherein the remote ends of the sides of the line are incidentally closed to form a loop circuit), the necessary tests to determine the location of a ground fault or cross with another conductor, or certain other tests, may be made while the wirechief simply occupies the time of the called subscriber by verifying the telephone number called; this conversation occupying, perhaps, from five to ten seconds. The subscriber, not suspecting that he has assisted in a testing operation, will have no reason to resent his being called. Moreover, the data obtained by the tester will be in terms which will not require their application to formulæ before having location significance. That is to say, the instrument will be direct-reading in that results in the desired unit will be observable in the instrument. The present testing instrument or bridge will also disclose for ready observation the data or factors of the test as well as the direct-reading results.

The present invention provides a testing bridge particularly adapted for use in locating faults by wirechiefs in charge of long distance toll lines, as well as by wirechiefs in charge of subscriber lines. Testing by wirechiefs is usually made under stress of demoralized service, so that simplicity in making the testing observations and rapidity and mechanical accuracy in arriving at results in concrete terms is a prime desideratum.

The testing instrument of the present invention may also serve as a milli-ammeter in determining current strength; in fact the instrument is normally a milli-ammeter, but having the adaptability of a testing bridge for measuring resistances and for locating faults by the well known Varley loop and other methods.

With reference to the accompanying drawings—

Fig. 1 shows a schematic circuit layout of

the fault locating apparatus of the present invention, test battery, ground connection, test keys on the wirechief's desk, a "B" operator's plug leading from a pair of line test jacks and a subscriber's telephone line leading to a line terminal jack cooperative with the "B" plug.

Fig. 2 shows a top elevation of the fault locating apparatus of the present invention embodied as a unit.

Fig. 2A shows a vertical section of the ratio arms mechanism shown in Fig. 2 taken along the line "A".

Fig. 3 shows a bottom elevation of the apparatus unit shown in Fig. 2, but with the balance indicator (milli-ammeter) removed.

Fig. 4 shows a detail of the movable scale 1 also shown in Fig. 2.

Fig. 5 shows a partial section of the upper or "1 to 1000" ohm rheostat shown in Figs. 1 and 2. The section is taken along the vertical center line of Fig. 2.

Fig. 5A shows a side view of the wedge for securing the rheostat ring 13 shown in Fig. 5 to the yokes 15.

Fig. 5B shows the front view of the wedge 29 shown in Fig. 5A.

Fig. 6 shows a bottom plan of the parts shown in Fig. 5, but with the protecting cover 30 and springs 36—29—40 removed.

Fig. 7 shows details of the operating handle 14 and the stem 35 therefor shown in Figs. 1, 2 and 5.

Fig. 8 shows a detail of the stem 35 and the sleeve 37 shown in Figs. 5 and 7.

With reference to Fig. 1, it will be noted that the resistor 5 joining the terminals 6 and 7 is adapted to form two resistors or so-called "A" and "B" ratio-arms between the terminals 6 and 7. The resistor 5 is merely indicative, so that the tap points thereon do not purport to exactly represent proportionate resistance values with reference to the resistor 5.

It will be noted from the designations that depending upon what tap-terminal a' to e' the contact-arm 8 is resting upon will determine the relative values of the "A" and "B" ratio-arms into which the resistor 5 will be thus divided. And, in view of the well known representation of Wheatstone bridge schematic diagrams, the portion of the resistor 5 between the contact-arm 8 and the terminal 6 will be referred to as the "A" arm, while the portion between the contact-arm 8 and the terminal 7 will be referred to as the "B" arm. The contact-arm 8 may be revolved about its pivot by its handle 9 to at will engage any one of the tap-terminals a' to e' , and the ratio of the resistance of the A arm to the resistance in the B arm will be as numerically designated contiguous to the respective tap-terminals.

It will be noted that the possible ratios between the resistances of the A and B arms

are 10 to 1, 1 to 1, 1 to 10, 1 to 100, 1 to 9 and 1 to 99. It will also be noted that in the case of the 1 to 9 ratio the sum of the component parts equals 10, or otherwise, the first power of 10. In the case of the 1 to 99 ratio the sum of the component parts equals 100, or otherwise the second power of 10. The value of the resistor 5 may be 1000 ohms, or other convenient value; the values chosen depending upon the voltage of the test battery employed, the sensitiveness of the milli-ammeter near its zero point, as well as the resistance of the circuits under test.

The rheostats 13 and 13', operated by handles 14 and 14', respectively, together form the so-termed adjustable-arm of the bridge. The so-termed adjustable-arm of the bridge therefore is the portion between the terminal 7 and the test binding-post 17. The so-termed X-arm of the bridge circuit involves the loop under test from the test binding-post 17 to terminal 6, and includes the normally short-circuited "check resistor" 19. The object of the check resistor 19 will be discussed presently.

Between the terminals 6 and 7 is connected the moving coil 20 of the "milli-ammeter", which latter includes an adjusting resistance 20', the value of which is determined when calibrating the milli-ammeter. An indicating pointer 21 is rigidly attached to the moving coil 20. A magnet having poles N and S and corresponding attached novel shaped pole-pieces N' and S' , respectively, influence the coil 20 when the latter is energized, in order to move the pointer 21 variably responsive with the strength of current traversing the coil 20. The ridges n' and s' in the pole-pieces N' and S' , respectively, aligning with the normal position of the coil 20 as shown in the drawings in order to give the coil 20 greater turning torque near the zero position. This is to insure a high sensitivity and amplified movement at or near the zero position of the pointer 21, with relatively low sensitivity at the outside portions of the scale. Furthermore, this provision is to obviate or reduce possible damage to the pointer from abnormal current in the coil 20. Due to the pointer deflection from zero being a function of the unbalanced condition of the bridge arms in tests the tester is enabled to anticipate the degree of unbalance and quickly balance the bridge circuits.

It will be noted that the "test battery" connected to binding-posts 22 and 23 is normally connected between the junction point (contact-arm 8) of the ratio-arms and the binding-post G'. The key Ba' is provided as an auxiliary or alternative means which may be used to apply the test battery to the bridge circuits if the key 27 is not used intermediate of the bridge binding-posts 17 and 18 and the line under test. Depressing button Ba will tie one pole of the test battery to faulty con-

ductor binding-post 17, as has been a well known practice in Wheatstone bridges, and as shown in the patents cited at the outset.

By inserting the "test plug" into the "line jack" or the "reverse line jack", the conductors of the "B" operator's plug will be serially included between binding-posts 17 and 18 when the receiver of the telephone on the "line under test" is removed from the switch-hook 24 and the "bridge test key" is operated by the key lever 26; the latter key causing the test battery binding-post G' to be connected with the binding-post 17, as does key Ba' when button Ba is depressed. This causes the (ungrounded) testing battery current to flow over the line under test and the bridge system, causing the milli-ammeter pointer 21 to deflect, provided the values in the four arms of the bridge system are not in balance, so-termed. Disregarding the ground fault, since the test battery is not now grounded, the result of the test will not be affected, regardless of which line jack leading to the "B" operator's plug the test plug is inserted into. If it is assumed that the contact-arm 8 is in engagement with tap-terminal a' as shown in the drawings, the A and B arms will have equal value so that the potential at the terminals 6 and 7 will be equal only when equal current strength traverses the A and B arms. This latter condition will only exist when the resistance included between the binding-posts 17 and 18 involving the loop of the line under test as one branch (so-termed X-arm), and the resistance introduced by one or both rheostats 13 and 13', as the other branch (so-termed adjustable-arm), are equal. The rheostats 13 and 13' are graduated. When rheostats (or only one of them) have been adjusted until the pointer 21 comes to zero position, as drawn, and wherein the current from the test battery is then divided equally over the A and B arms, and the line or X-arm and the adjustable-arm, respectively, the adjustable-arm involving the rheostats 13 and 13', the total indicated included ohmic resistance value in the rheostats 13 and 13' will exactly equal the X-arm ohmic resistance.

If it is assumed that the contact-arm 8 is in engagement with the tap-terminal f', the ratio of the A arm to the B arm will be 1 to 10, so that to obtain a balanced condition of the bridge system with the test battery ungrounded the total value introduced by the rheostats 13 and 13' will be ten times the resistance of the line under test; that is, the resistance of the line under test (X-arm) will be the indicated adjusted numerical value of the said rheostats, after pointing off one decimal place to effect the division by ten. In the same manner, if the contact-arm 8 is placed on the tap-terminal d', the ratio of the A arm to the B arm will be 1 to 100, so that to obtain a balanced condition the total value

introduced by the rheostats 13 and 13' will be one-hundred times the resistance of the line under test; that is, the resistance of the line under test will be the indicated numerical adjusted value of the rheostats 13 and 13', after pointing off two decimal places to effect the division by one-hundred. In the same manner, if the contact-arm 8 is placed on the tap-terminal b', the ratio of the A arm to the B arm will be 1 to 9, so that to obtain a balanced condition, the total value introduced by the rheostats 13 and 13' will be nine times the resistance of the line under test; that is, the resistance of the line under test will be the indicated numerical adjusted value in the rheostats 13 and 13', after dividing by nine. However, this latter ratio not being a decimal ratio, will not usually be chosen for determining the loop resistance simply. It has other objects, as will appear presently.

It will be clear that if the switch CR' is operated wherein the normal short-circuit is removed from the check resistor 19, it will be equivalent to adding 1000 ohms resistance in series with the line conductors under test; more particularly, the conductor of the line under test leading to the binding-post 18.

Assume that the test plug is inserted into the jack leading to the "B" operator's plug, and the "B" operator's plug is then inserted into the "line terminal jack", and the key lever 26 is thrown to operate the bridge test key. It will be noted that under this condition the line conductor having the "ground fault" will be the one leading direct to the binding-post 17. Had the test plug been inserted into the "reverse line jack", this faulty line conductor would then lead direct to binding-post 18. It is necessary, in making the Varley loop test for a ground fault (or cross fault which may be resolved into an essentially equivalent fault condition by grounding one of the crossed conductors) to have the faulty conductor lead directly to the binding-post 17 which is designated "Faulty." This is so the faulty conductor will be in direct, adjacent connection with and in series relation with the rheostats 13 and 13', the requirement of which will appear presently.

Assume further, with relation to the last foregoing assumption, that the contact-arm 8 is placed on tap-terminal f'. Also, that when now operating either rheostat 13 or 13', the corresponding contact spring 36 or 36' shown resting upwardly against the corresponding stem 35 or 35' will be operated (by depressing handle 14 or 14' as the case may be) into the respective shown dotted positions in order to apply binding-post 22 to grounded binding-post 28, in lieu of through springs 39', 39, key spring 27 of the operated bridge test key, to binding-post 17. Under this condition, ground-seeking test battery will be applied through contact-arm 8 over a

branched path to the ground fault through the A and B arms, wherein the A arm has one-tenth the ohmic value of the B arm, as follows: From terminal 6 one said branch is through the normally closed contacts of the key CR', binding-post 18, good conductor of the line under test, receiver of the telephone off the switch-hook 24, remote portion of the faulty conductor of said line to the ground fault. From terminal 7 the other said branch is through the rheostats 13 and 13' (which are adjustable from zero value), binding-post 17, near portion of the faulty conductor of said line to the ground fault. The milliammeter will indicate unequal potential between terminals 6 and 7 unless ten times as much current from the test battery traverses the branch including the A arm as that traversing the B arm, and this will only ensue when the path traced through the B arm and the ground fault includes ten times as much resistance as the path through the A arm to the ground fault. If it is assumed (though not necessarily so) that the line conductors of the line under test are approximately of the same resistance per unit of length, and of approximately the same length, it will be obvious that resistance will need to be introduced by the rheostats 13 and 13' to bring about the balance of current potential between the terminals 6 and 7, since it is improbable (as will be assumed for the present) that the resistance to the fault from binding-post 18 on the faulty conductor is less than one tenth the resistance from the fault through the telephone to the binding-post 17. The total value of the resistance introduced by rheostats 13 and 13' to balance with the point of fault on the line used as the fulcrum, and with the test battery grounded will be referred to as the "r" resistance.

The well known equation of the Varley loop test where unequal ratio-arms values are employed is:

$$45 \quad \frac{BL - Ar}{A + B} = \text{distance in ohms}$$

to the fault (from the binding-post 17) on the faulty conductor, wherein B and A denote the numerical values of the A and B arms, respectively; L denotes the resistance of the line under test (including the receiver off the switch-hook) between the binding-posts 17 and 18; r denotes the value included by the rheostats 13 and 13' to effect the balanced condition last referred to with the test battery grounded. So, if the loop resistance of the line under test is, for example, 423 ohms, as determined by one of the tests referred to for determining simple resistance in the X-arm with the test battery ungrounded, or this resistance is known to the tester from previous determinations, and the value of "r" as last determined (with

battery grounded) is, for example, 3691, the equation when substituted becomes:

$$10 \times 423 - 1 \times 3691 = \frac{4230 - 3691}{11} = 49 \text{ ohms} \quad 70$$

out to the fault on the faulty conductor from binding-post 17.

If any other ratio between the A and B arms were taken when balancing with the test battery grounded, the substitution would be made in the same manner. For example, if the ratio of resistance between the A and B arms is taken as 1 to 9, as would ensue if the contact-arm 8 were moved into contact with the tap-terminal b', and the value of "r" (with test battery grounded) is then observed to be 3317, the substituted equation becomes:

$$9 \times 423 - 1 \times 3317 = \frac{490}{10} = 49 \text{ ohms} \quad 85$$

as the resistance out to the fault on the faulty conductor from binding post 17.

If said adjusted value 3317 is not removed from the rheostats 13 and 13' and a loop resistance observation (with test battery ungrounded), is then taken by increasing the value involved in the rheostats 13 and 13', with the handles 14 and 14' undepressed and without first restoring the respective rheostats 13 and 13' to zero resistance value, it will be found that 490 ohms additional will have to be introduced to effect a balance of the pointer 21 of the milli-ammeter. This is ten times the ohmic resistance to the fault on the faulty conductor.

That is, taking a balance with the test battery grounded and with the 1 to 9 ratio-arms setting, and then taking a balance with this same 1 to 9 ratio-arms setting, but with the test battery not grounded, the difference between the two balance values introduced by the rheostats 13 and 13' in the successive two tests where a balance is obtained in each instance, will be ten times the ohmic value from the binding-post 17 to the fault on the faulty conductor. So, in choosing this ratio-arm relation of 1 to 9, a first balance may be taken with the test battery grounded, and a second balance then taken with the test battery looped (wherein the last ohmic value will inherently always be as large or larger than the former), and by pointing off one decimal place from the difference in the observations, obtain the ohmic value included from binding-post 17 to the fault on the faulty conductor connected directly thereto. This is regardless of the disparity of the ohmic value per unit of length of the conductors of the line under test, and the ohmic value of the conductor (subscriber's telephone in the present instance) joining the remote ends of the line conductors of the line under test, wherein the resistance of the ground fault and the poten-

100
105
110
115
120
125
130

tial of the ground fault will not be a factor in the result.

It will be clear, presently, that when making the last assumed test wherein the contact-arm 8 is in contact with the tap-terminal b' , and wherein the ratio of the A arm to the B arm is 1 to 9, that the actual or numerical value of the loop resistance of the line under test with test battery ungrounded is not graphically recorded or noted, nor is it necessary to graphically record or note the actual numerical value of the " r " resistance required to balance one portion of the subscriber's loop against the other with the point of ground fault as the fulcrum. However, the difference in these observations, as read directly from the bridge, is considered and divided by ten by pointing off one decimal place. The first adjustment to balance of the rheostats 13' and 13 wherein the test battery is grounded gives the numerical value of " r " required by the Varley loop equation, but not noted by the tester as an element of the calculation, since this value is only used to set up a condition in the circuits of the bridge for a subsequent observation of the specific line under test. The value of " r " can be zero, but it can never have a negative value in an effective test. If the observation should lead to a negative value in any setting of the ratio-arms, a higher ratio as between the A and B arms will be required in order to obtain a balance, or the check resistor 19 will need to be introduced. This negative value can only exist if the resistance to the fault on the faulty conductor from binding-post 17 is greater than over the good conductor from binding-post 18 around the remote end of the line under test to the fault, as can occur if the faulty conductor is of relatively high resistance per unit of length wherein the faulty conductor is "paired" for test with a good conductor of relatively low resistance per unit of length. In this respect, the present bridge does not behave differently from well known Wheatstone bridges when used for making the well known Varley loop test; in fact, the referred to test the present bridge executes is essentially the Varley loop test, but wherein the present bridge, through its peculiar construction and ratio-arm adaptability solves by inherent process and in terms of the desired units incident to taking the observations for the Varley loop data of the circuit conditions with respect to the line under test.

It is thought that in imparting a full understanding of the theory and operation of the present bridge, in so far as reasons for the results hereinbefore generally set forth is concerned, a fuller discussion will not be required, since my patents made of reference at the outset sets forth the theory quite comprehensively. Therefore, actual results, rather than reasons for them, will only be re-

quired in imparting a full and clear understanding of the present invention.

With reference to Fig. 2, parts schematically shown in Fig. 1 are shown in detail correspondingly indexed. The scale 31 is 70 made of thin metal as shown in section in Fig. 5. This scale 31 is fastened by four screws 32 to the mounting plate 33. The scale 1 fits revolvably within the scale 31 and is held against being removed by a beveled edge 34 cooperative with the inner circumference of scale 31. The scale 1 is shown in detached detail in Fig. 4. The scale 31 is shown only partly graduated, but it is to be understood that the graduations extend all 80 the way around; each indicated division corresponding to 50 ohms, so that the 20 divisions comprise a range of 1000 ohms in the exemplified embodiment. The scale 1 has 85 divisions and graduations radial with the 90 graduations of scale 31, as well as having 95 graduations of one-half values, and may have others not shown.

By reference to Figs. 5 and 8, the construction of the stem 35 and the handle 14 and co-operating parts thereof will be understood in view of the descriptions to follow. The insulated point of the stem 35 normally rests on the spring 36, so that this spring, through its tension, keeps the stem 35 at its up position, as shown. The stem 35 is rigidly fastened to or made integral with the handle 14 by moulding the said handle on the said stem, the handle being preferably made of insulating material. A sleeve 37 fits revolvably 100 through the mounting-plate 33, positioned by the shoulder 38. The sleeve 37 can thus be telescoped into the handle 14 as shown by the dotted lines in Fig. 7 when the stem 35 is moved downward by depressing the 105 handle 14 against the tension of the spring 36, wherein the spring 36 is disengaged from the spring 39 and engaged with spring 40 as indicated by the dotted position of spring 36.

A finger 42 is rigidly fastened to the stem 35 by the finger 42 passing through the stem 35. The sleeve 37 has an elongated hole 43 in the right-hand side to admit the finger 42 and to permit the stem 35 carrying the finger 42 to be pushed or depressed downward. The stem 35 may be turned clockwise from the drawn normal position by the handle 14, and returned to normal position at will by turning the handle 14 counter-clock-wise. A retaining pin 44 passes 110 through the stem 35 flush with the lower face of the mounting plate 33 to limit the upward movement of the said stem, and a stop-screw 37^a is set into the sleeve 37 at right angles to the pin 44 to prevent the sleeve 37 being freely removed, as otherwise the stem 35 and sleeve 37 would be subject to being lifted upward, clear of the mounting-plate 33. The pin 44 extends through the slots 44^a on opposite sides of the sleeve 37 as shown by the 120 125 130

dotted lines in Figs. 5, 6 and 7, so the pin 44 also serves to revolve the sleeve 37 carrying wiper 48 when the stem 35 is revolved by the handle 14.

5 It will be noted that the finger 42 has a curved free end which has a wedge-shaped point 45. Cooperative with the said point of the finger 42 is a notch 47 of the scale 1 into which the point 45 of the finger 42 will register when the handle 14 is depressed, which latter operation incidentally operates the spring 36 into its dotted position.

It will thus be clear that when the handle 14 is turned while depressed, the scale 1 will be carried through a corresponding angular distance. Also, that when the scale 1 is being moved by the finger 42 the spring 36 will be in its dotted position 36.

The wiper 48 engages the top edge of the wound circular rheostat 13 (also indicated schematically in Fig. 1), so as the stem 35 revolves from normal position resistance will be introduced by rheostat 13. The wiper 48 is secured to the sleeve 37, but is insulated therefrom by the insulation bushing 49. A coil conducting-spring 50 has one end attached to the insulated pin 51, which latter is set into the mounting-plate 33, and the other end of the spring 50 is attached to the pin 52 which is set into the wiper 48, so that the pin 51 is permanently electrically tied to the wiper 48 and both the pin 51 and the wiper 48 are insulated from the mounting-plate 33. This arrangement is provided so that a solid electrical connection of unvarying resistance is provided to the wiper 48.

A pointer 54 is rigidly fastened to the upper face of the shoulder 38 by screws, brazing, or any suitable method, so that it will indicate the angular position the stem 35 and the wiper 48 is turned from the normal position shown in the drawings.

45 A stop 56, which is the head of a downwardly tapered machine screw, prevents the scale 1 moving past normal position when returned to normal when the handle 14 is turned counter-clock-wise wherein the end of the pointer 54 will engage the screw 46. The tapered head of the screw 56 permits ready 50 adjustment of the scale 1 to zero position by turning the screw 56 one way or the other as required. The screw 46 is similar to screw 56 and can be turned to adjust the zero position of the pointer 54.

55 From the foregoing, it will be clear that the handle 14 can be depressed before turning so that the end of the finger 42 will engage the right-hand face of the notch 47, so that when the handle 14 is then turned
60 clock-wise the scale 1 and the wiper 48 will correspondingly revolve, while the spring 36 will assume the dotted position 36. Then, if the downward pressure is removed from the handle 14 to cause the end of the finger 42 to
65 disengage the notch 47 and the spring 36 to

restore to normal, the stem 35 carrying wiper 48 can be moved still further ahead. Under the latter condition, the scale 1 will remain where last moved, while the wiper 48 moves as before with the stem 35 to which it is rigidly attached. The graduations on the scale 31 opposite to the "0" graduation on the scale 1 will then indicate how many ohms were introduced by the rheostat 13 when the balance with the battery grounded was obtained, while the graduation on the ring 31 opposite the pointer 54 when the handle 14 is brought to the final stop in the clock-wise movement, will indicate how many ohms are introduced by the rheostat 13 at that time. 80

It is not thought necessary or desired to detail the operation of the designated "Thousands" dial beyond stating that a prime is added to the index numeral of parts corresponding to parts of the designated "1 to 1000" dial. In place of using a wire coil circular rheostat as 13, the rheostat 13' is made up of nine 1000 ohms resistor coils 61 to 69 connected in series wherein contact points 71 to 79 are cooperated by wiper 48' 85 to introduce the said resistor coils in series in correspondence with the tap-contact point 71 to 79 the wiper 48' is resting upon. The wiper 48' normally rests on contact 70 wherein no resistance is introduced. Thus, in place 90 of introducing small ohmic values involved in the respective turns of wire of the rheostat 13 directly engaged by the wiper 48, the resistor coils 61 to 69 of 1000 ohms each are successively introduced in series by the 95 wiper 48' by steps of 1000 ohms as contacts 71 to 79 are engaged by wiper 48'. 100

From the last foregoing statements it will be clear that where the resistance value required to effect a balance is greater than comprehended by the rheostat 13, the rheostat 13' will be brought into requisition. For example, if when making the first balance with the handle 14 depressed (and this will always be the condition of the first observation in a Varley loop test wherein the test battery will have one of its poles (the negative in the exemplified instance) applied to ground, no balance can be secured, even by turning the handle 14 (clock-wise) until all the resistance (1000 ohms in the exemplified instance) of the rheostat 13 has been introduced, the handle 14 is revolved back (counter-clock-wise) to zero position and the handle 14' depressed and then turned until the milli-ammeter indicates a balance has been passed. That is, that too much resistance has been introduced. The handle 14' is then turned counter-clock-wise so that the wiper 48' rests on the first antecedent contact 71 to 79 and the handle released so that spring 36' assumes its normal position. If it is assumed that the said first antecedent contact is 75, 5000 ohms have been introduced by rheostat 13'. The handle 14 is next depressed, and since less than 1000 ohms are required by the 110

ohms will be required to effect the balance, the balance can be effected by then turning the handle 14 clock-wise from its zero position. When the balanced condition is attained, as indicated by the milli-ammeter, the handle 14 will be released so that the spring 36 can restore to its normal position.

Assume that the point of balance is obtained when the pointer 54 is opposite the graduation indicating 673 ohms. Then, the combined resistance introduced by rheostats 13 and 13' is 5673. This operation will be the same regardless of the ratio value used, though it is obvious, in view of my patents made of reference at the outset, that the ratio value as between the A and B arms will directly affect the amount of resistance required to effect a balance. For example, if a ratio of 1 to 99 as between the A and B arms were used in the observation requiring the 5673 ohms to effect a balanced condition, this amount of resistance would be reduced had a smaller ratio, such as 1 to 9 or 1 to 1 been chosen, but, of course, not in direct relation. The ratio chosen will depend upon the resistance and position of the fault in the line under test, the resistance of the loop under test, as well as the degree of accuracy required. It is not taken into account by the tester at this stage of the test.

The adjusted value obtained as last described corresponds to the "r" element appearing in the Varley loop equation. Now, to obtain the final balance, involving the "L" element appearing in the Varley loop equation, the handles 14' and 14 will be successively revolved clock-wise from where left in making the first observation, but this time without depressing the handles 14' or 14, and a balanced condition sought as before, since the circuits will be found out of balance due to the springs 36 and 36' being at normal wherein the test battery is ungrounded. The resistance to the ground fault from the faulty post 17 on the faulty conductor will be the sum of the readings indicated by the pointers 54 and 54' on the movable scales 1 and 1', divided by 2, 10 or 100, depending upon if the ratio of the A ratio-arm to the B ratio-arm is 1 to 1, 1 to 9, or 1 to 99, respectively. It will be noted that the scale 1 has graduations in half values radial with the full values. This is to make the division by 2 more convenient when the 1 to 1 ratio is used. Where higher accuracy is desired, the 1 to 9 or 1 to 99 ratio between the A and B arms will be employed, as the rheostat 13' will then ordinarily involve most of the resistance introduced, the coils of which may be calibrated to greater accuracy than the wound rheostat 13. However, in most instances the resistance of the line under test will come within the range of the 1 to 1000 ohm rheostat so that a Varley loop test with it alone may be made in a few seconds.

It will be clear from the last test described that where the Varley loop test is to be made, the A and B arms are first set to the desired ratio. Then the handle 14' is depressed to operate spring 36' to ground the test battery, while at the same time turning the handle 14', until a point is reached where if it is turned further the milli-ammeter will indicate a reversed out of balance condition. The pressure on handle 14' is then released so that 70 spring 36' restores and scale 1' is disengaged by the finger 42. The handle 14 is then depressed to operate the spring 36 to ground the test battery while at the same time turning the handle 14 until a point is reached whereat the 80 milli-ammeter needle 21 will indicate a balance of the circuits. The pressure on the handle 14 is then released so that the spring 36 restores and the scale 1 is disengaged by the finger 42. The rheostats 13 and 13' now 85 involve the so-termed "r" resistance observed when making the well known Varley loop test with bridges heretofore used and wherein this data is applied to the usual equation for such herein before given. However, the 90 tester takes no account of this "r" value which is left indicated by the off-normal position of the scales 1' and 1.

The next operation is that of balancing the bridge with respect to the loop resistance of 95 the line under test with the battery for testing ungrounded. This is accomplished by first turning the handle 14' and then the handle 14 from the respective positions assumed by the antecedent observation wherein the test 100 battery was grounded; this time the handles 14' and 14 not being depressed to operate the springs 36' and 36 to ground the test battery. That is, the last observation will include all 105 the resistance introduced in the first observation, with any additional resistance required. The reading taken from the movable scales 1' and 1 as indicated by the pointers 54' and 54 will represent the distance to the ground fault on the faulty conductor. However, this value 110 will have to be divided by 2, 10 or 100, depending upon if the ratio of the A arm to the B arm is 1 to 1, 1 to 10 or 1 to 100, respectively.

If an ordinary loop resistance measurement is to be taken, wherein the resistance of the bridge leading-out conductors to the "B" operator's plug is to be subtracted, the ratio-arms setting may be 1 to 1, 1 to 10 or 1 to 100. The bridge leading-out conductors will be short-circuited at the "B" operator's plug. 115 The two rheostats 13' and 13 will then be adjusted without depressing the handles 14' and 14 (rheostat 13' being adjusted first) in order 120 to not ground the test battery. When a balanced condition is obtained the scales 1' and 1 are revolved until the "0" markings of the 125 scales 1' and 1 register radially with the adjusted position of the pointers 54' and 54. The short-circuit is then removed from the leading-out conductors so that the line under 130

test will be included between the posts 17 and 18 and the rheostat 13' adjusted; followed by adjusting rheostat 13, but without first restoring either to its zero (normal) position. That is, the dials 14' and 14 are moved ahead from the last adjustment, having in mind that possibly both rheostats will not require adjusting, depending upon the ohmic value of the line under test. Remembering that the scales 10 1' and 1 have been moved into a false zero position, the reading will now be taken with reference to these scales to obtain the net loop ohmic value to the line under test. That is, if a 1 to 1 ratio of the A arm to the B arm 15 is used, it will be the numerical value exclusive of the resistance of the leading-out conductors. The indicated reading on the scales 31' and 31 will represent the total value between the posts 17 and 18, which includes the 20 bridge leading-out conductors to the "B" operator's plug.

If the ratio of 1 to 10 or 1 to 100 had been used between the A arm and the B arm, the reading of the scales 1' and 1 combined or 25 31' and 31 combined will be divided by 10 or 100, respectively. It will therefore appear that if a number of lines are to be measured for loop resistance wherein the same ratio between the A arm and the B arm is to 30 be retained, the false zero determined by the position of the scales 1' and 1 will be used as a starting or zero point in each measurement, and not necessarily the absolute zero point as shown by the position of the pointers 35 54' and 54 in the drawings. Changing the ratio between the A arm and the B arm will, of course, require a new adjustment to false zero for the scales 1' and 1. Under this method of taking loop resistance measurements 40 the bridge will show the leading-out conductor resistance (represented by the false zero off-normal position of the scales 1' and 1) and the net under test loop resistance, with due regard to the ratio between the A and 45 B arms.

The rheostat 13, consisting preferably of a spiral coil of resistor wire bent into circular shape, is held to the mounting-plate 33 by two yokes 15 wherein four insulation 50 wedges 29 shown in detail in Figs. 5A and 5B are applied; one at each end of each yoke, shown in Fig. 6. A sheet-metal strip 30 is secured by pins 31 to a face of the wedge and bent over after the wedge is set into position, 55 shown in Fig. 6, so that the wedge cannot be removed without straightening the bent-over portion 30. The yokes 15 are insulated by sheet insulation, or other, where they come into contact with the rheostat winding. The 60 coils of the rheostat 13' may be simple resistor coils, such as have been used in well known Wheatstone bridges.

The milli-ammeter is secured into place by means of four bolts 55 by nuts 57, wherein 65 there are washer-plates 58 on the upper side

of the magnet 53 of the milli-ammeter and washer-plates 59 below the magnet. Separator sleeves 60 serve to space the magnet 53 below the yokes 15. Each yoke 15 is secured by four machine screws 16 to the mounting- 70 plate 33. The milli-ammeter pointer 21 moves over the scale 25 visible from the top.

The contact springs 36, 39 and 40 are insulated from each other and mounted on a washer-plate 88, which latter, with springs 75 and insulating separators are attached by screws 41 to the yokes 15. The employment of the springs 36, 39 and 40, operated by the stem 35, and also the springs 36', 39' and 40', operated by the stem 35' are salient features 80 of the present invention, whereby the test battery can be grounded incidental to depressing either handle 14 and 14' in order to engage the scale 1 or 1', respectively.

Another salient feature of the present invention is the special shaping of the pole-pieces N' and S' of the milli-ammeter magnet 53 to make the sensitiveness of the milli-ammeter more pronounced at and near the 90 zero position.

In case it is desired to determine the current strength flowing in the line under test wherein a battery source, not shown, is included in the path of the test plug conductors, the key lever 26 will be thrown to operate the 95 "milli-ammeter" key. Assuming that under the condition the circuits of the bridge proper are as shown in the drawing Fig. 1, it will be seen that the milli-ammeter winding 20 and series resistor 20' will be shunted by the resistor 5, but in series with the line under test, and being graduated to read in milli-amperes in the present exampled instance will indicate the current flow over the test plug conductors in milli-amperes. Thus, the present 100 invention, as stated at the outset is, in fact, normally a milli-ammeter, but having adaptations for using it as a testing bridge wherein the Varley loop test can be made, as well as ohmic resistance determined by the Wheat- 11 stone bridge method.

The ratio-arm adjuster having contact-arm 8 is operated by handle 9, designated "Ratio" wherein the contact-arm 8 successively engages the tap-terminals a', b', c', d', 11 e' and f', and continuously engages the conducting ring 86; the latter being connected at lug 88 to conductor 77 shown in Fig. 1. The said tap terminals and ring 86 are mounted on an insulated member 87 which is separated 12 from the mounting-plate 33 by four sleeves 80 which have four machine screws 81 passing through them into the mounting-plate 33. The pointer 83 is rigidly secured to the stem 84 with radial correspondence with the contact-arm 8, so that it will indicate on the upper face of the mounting-plate 33 the location of the contact-arm 8 with respect to the cooperating tap-terminals a' to f'. The stem 84 is threaded for a nut 85 at its lower end. 13

and a flat surface (not shown) of the side of the circular stem 84 registers with a hole cooperative therewith in the contact-arm 8, so that the contact-arm 8 will be rigid with respect to the stem 84, so far as any turning of the stem 84 about its axis is concerned. The handle 9 is rigidly attached to the top end of the stem 84. It will thus be clear that the handle 9 and the contact-arm 8 can be continuously turned in either direction at will in setting the ratio-arms involved in resistor 5 with any indicated ratio-arm relation.

The check resistor 19 is introduced by depressing the self-restoring key button CR to operate key CR' when it is desired to introduce more resistance in the line conductor leading from the binding-post 18. This may (but not necessarily) be when the faulty conductor is adjacent to binding-post 18 in a reverse test (out over the good conductor) and it is desired to make the resistance between the binding-post 17 and the fault less than the resistance between the binding-post 18 and the fault, having in mind that when a ratio between the A and B arms of 1 to 1 is used the resistance from the binding-post 17 to the fault must be lower or as low as the resistance from the binding-post 18 to the fault in order to execute a test, and also having in mind that in practice both conductors in a loop under test may not have the same cross section, resistance per unit of length, or length. The check resistor 19 thus lends itself to, in effect, increase the resistance of the good conductor (or the faulty conductor if it is adjacent to the binding-post 18 in a reverse test) if it has a relatively low resistance which, due to the location of the fault, may make the resistance from the binding-post 17 to the fault greater than the resistance from the fault to the binding-post 18. Under the latter condition, without the check resistor 19 included, a balance with a 1 to 1 ratio between the A and B arms could not be effected, because adding resistance by rheostats 13' and 13 in the arm adjacent to the binding-post 17 would then only increase the unbalance.

The check resistor 19 thus lends itself to making a reverse test using a 1 to 1 ratio between the A and B arms wherein the sum of the conductor resistances to the fault out over the respective two conductors of the line under test should equal the loop resistance, if a single fault exists. One of the latter tests will require that the resistor 19 be introduced in order to meet the stated condition of a 1 to 1 ratio between the A and B arms, which is that the resistance to the fault from binding-post 17 must be less than from binding-post 18.

In practice, the faulty conductor (or the conductor the location measurement is to be applied to) will not always be the one leading

to the sleeve spring of the line jack, and in that case the reverse line kick will be employed in order to place the conductor it is desired to measure out to the fault upon adjacent to the binding-post 17.

The screws 90 shown in Fig. 2 are for fastening the protecting cover 2 to the mounting-plate 33; lugs thrown out from the cover 2, not shown, being threaded to receive the screws 90.

The bearings for the spindle of the coil 20 of the milli-ammeter are not shown in order to simplify the drawings, but any desired known method may be employed, the milli-ammeter not involving invention over well known milli-ammeters excepting as to the ridges n' and s' in the pole-pieces N' and S', respectively, the objects of which have been set forth.

It has been stated that the mechanism for operating the rheostat 13' is like that for operating rheostat 13. While this is true, in general, the mechanism for rheostat 13' below the mounting-plate 33 differs in detail. For example, the shape of the wiper 48' which makes contact upwardly thus obviates the use of a screw corresponding to 37'. Also, the yoke 15' corresponding to one of the yokes 15 is fastened by four screws 16' directly to the mounting-plate 33. The set of springs 36-39-40 are mounted by screw 41' to the yoke 15' so the spring 36' has the same relation to the end of the stem 35' as spring 36 has to similar stem 35. The electrical connections with relation to coils 61 to 69 are shown in Fig. 1.

The "bridge test key" and the "milli-ammeter key" are only two of a possible number of keys operatively associated with the "test plug". For example, there would usually be a listening key for connecting the wirechief's telephone through condensers to the conductors of the "test plug" so the wirechief may listen or talk over the connection to the subscriber's telephone while conducting a test of the subscriber's line, the condensers making the wirechief's listening taps opaque to the direct current from the test battery.

The ridges n' and s' of the milli-ammeter pole-pieces may be varied in shape. For example, the edges of the ridges may protrude a less distance than the center. That is, the center of the ridge parallel with the axis of the moving coil will come nearer to the coil than the edges. Moreover, the edges of the ridges may curve the opposite way from that shown in the drawings, all depending upon the characteristic scale graduation desired.

The present invention is capable of detailed modification without departing from its scope as defined by the subjoined claims; for example: The stem 35 in place of being circular in cross section may be fluted lengthwise in order to reduce the friction against free endwise movement. Again, the fric-

tion against this endwise movement may be reduced by roller or ball-bearings. The sleeve 37 may be revolved in a ball-bearing in place of the simple bearing shown, in order to permit it to revolve more freely. The movable scale 1 may revolve on a ball-bearing concentric with its axis, in order to make it revolve more freely, in place of revolving within its periphery as shown. The said bearing changes will promote ease and rapidity of 10 operation in executing tests.

Having set forth an exemplary embodiment of the invention, what I claim is:—

1. In a rheostat, a resistor, a circuit adapted for including said resistor, a wiper for 15 making contact along the resistor so as to introduce resistance of said resistor into the circuit, a graduated scale for indicating the resistance included by the resistor through 20 the agency of the wiper movement, a handle for operating said wiper, means for operating the scale by the handle coincident with operating the wiper, means for further operating the wiper by the handle in a second 25 stage movement to introduce more resistance by the resistor without further operating the scale, and means whereby the graduations on said scale as defined by the final 30 position of the wiper will numerically indicate the value of the resistance introduced by the resistor only by the second stage of its movement.

2. In a rheostat, a resistor, a circuit adapted for including said resistor, a wiper for 35 making contact along the resistor so as to introduce resistance of said resistor into the circuit, a movable graduated scale for indicating the resistance included by the resistor through 40 the agency of the wiper movement, a handle for operating said wiper for thereby introducing resistance by the resistor, a catch-finger of said handle, means whereby depressing the handle by pressure will engage the catch-finger with the movable scale, 45 means whereby then moving the handle will correspondingly move the scale and wiper, means whereby removing the pressure from the handle will disengage the catch-finger, means whereby then moving the handle in a 50 second stage movement will correspondingly move the wiper while the scale remains where last moved, and means whereby the graduations on said scale defined by the final position of the wiper will numerically indicate 55 the value of the resistance included by the resistor only by the second stage of its movement.

3. In a rheostat, a resistor, a circuit adapted for including said resistor, a wiper for 60 making contact along the resistor so as to introduce resistance of said resistor into the circuit, a movable graduated scale for indicating the resistance included by the resistor through 65 the agency of the wiper movement, a handle for operating said wiper, a catch-

finger of said handle, means whereby depressing the handle by pressure will engage the catch-finger with the movable scale, and means whereby removing the pressure from the handle will disengage the catch-finger. 70

4. In a rheostat, a resistor, a circuit adapted for including said resistor, a wiper for making contact along the resistor so as to introduce resistance of said resistor into the circuit, a movable graduated scale for indicating the resistance included by the resistor through 75 the agency of the wiper movement, a handle for operating said wiper, a catch-finger of said handle, means whereby depressing the handle by pressure will engage the catch-finger with the movable scale, means whereby removing the pressure from the handle will disengage the catch-finger, and means whereby then moving the handle will correspondingly move the wiper while 80 the scale remains where last moved before removing the pressure. 85

5. In a rheostat, a resistor, a circuit adapted for including said resistor, a wiper for making contact along the resistor so as to introduce resistance of said resistor into the circuit, a first graduated scale for indicating the resistance included by the resistor through 90 the agency of the wiper movement, a second movable graduated scale, a handle for operating the wiper, means for operating the movable scale in a first stage movement by the handle coincident with operating the wiper, means for further operating the wiper by the handle to introduce more resistance by 95 the resistor without further operating the scale, and means whereby the position of the wiper with respect to the graduations on the movable scale will indicate the resistance included by the resistor only by the second stage of the wiper movement. 100

6. In a rheostat, a resistor, a circuit adapted for including said resistor, a wiper for making contact along the resistor so as to introduce resistance of said resistor into the circuit, a first graduated scale for indicating the resistance included by the resistor through 110 the agency of the wiper movement, a movable graduated scale for indicating the resistance included by the resistor through the agency of the wiper movement, a handle for operating the wiper in a first stage movement for thereby introducing resistance by the resistor, a catch-finger of said handle, means whereby depressing the handle by pressure will engage the catch-finger with the movable scale, means whereby then moving the handle will correspondingly move the movable scale and wiper, means whereby removing pressure from the handle will disengage the catch-finger, means whereby then moving the handle in a second stage movement will correspondingly move the wiper while the movable scale remains where last moved, means whereby the graduation on the 115 120 125 130

- movable scale defined by the final position of the wiper will numerically indicate the value of the resistance included by the resistor only by the second stage movement, and 5 means whereby the graduation on first said scale defined by the final position of the wiper will numerically indicate the total value of the resistance included by the said wiper movements.
10. 7. In a rheostat, a resistor, a circuit adapted for including said resistor, a wiper for making contact along the resistor so as to introduce resistance of said resistor into the circuit, a first graduated scale for indicating 15 the resistance included by the resistor through the agency of the wiper movement, a second movable graduated scale, a handle for operating the wiper, means for operating the movable scale in a first stage movement by the handle coincident with operating the wiper, means for further operating the wiper by the handle to introduce more resistance by the resistor without further operating the scale, means whereby the position 20 of the wiper with respect to the graduations on the movable scale will indicate the resistance included by the resistor only by the second stage of the wiper movement, and means whereby the position of the wiper 25 with respect to the graduations on the first scale will indicate the total resistance included by the resistor by the said wiper movements.
8. In a measuring instrument, a rheostat, 30 a gyrating wiper for making contact along the resistor constituting the rheostat to alter the effective resistance of the rheostat, a circular graduated scale for indicating the resistance included by the rheostat, a handle 35 for operating said wiper, means for operating the scale to revolve it about its axis coincident with operating the wiper, means for further operating the wiper by the handle in a second stage movement to introduce additional resistance into the rheostat without further operating the scale, and means 40 whereby the graduations on the scale as defined by the final position of the wiper will numerically indicate the value of the resistance introduced in the rheostat only by 45 the second stage of its movement.
9. In a Wheatstone bridge for executing a Varley loop test, a handle for operating the rheostat constituting the adjustable arm 50 of the bridge, a movable scale of the rheostat, means for operating the movable scale by the handle, a current indicator for denoting a balanced condition of the bridge and loop under test, means responsive to the 55 handle for bringing about the two different balance conditions of the Varley loop test indicated by the indicator, means whereby the scale will be operated only while the handle is operated to bring about the first one 60 of said balance conditions, and means whereby the position assumed by the handle with relation to the scale to bring about the second one of said balance conditions will be a decimal function of the resistance in ohms from the bridge out to the fault on the faulty conductor of the loop under test.
10. In a Wheatstone bridge for executing a Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, and means whereby the position assumed by the handle with relation to the scale to bring about the second one of said balance conditions will be a numerical function in a power of ten of the resistance in ohms from the bridge out to the fault on the faulty conductor of the loop under test.
11. In a Wheatstone bridge for executing a Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, and means whereby the position assumed by the handle with relation to the scale to bring about the second one of said balance conditions will be an even multiple of the resistance in ohms from the bridge out to the fault on the faulty conductor of the loop under test.
12. In a Wheatstone bridge for executing a Varley loop test, a handle and rigidly connected pointer therefor for operating the rheostat constituting the adjustable arm of the bridge, an X-faulty post at the outer end of said adjustable arm, a movable scale of the rheostat cooperative with the pointer, means for operating the movable scale by the handle, a source of testing current, a current indicator for denoting a balanced condition of the bridge and loop under test, a switch for changing the battery connection from the X-faulty post to ground so as to apply the battery through the ratio arms in branch over the loop to the point of ground fault, means responsive to the operation of the handle for bringing about said operation of the switch and for also bringing about two

different balance conditions of the Varley loop test indicated by the indicator, means whereby the scale and also the switch will be operated only while the handle is operated to bring about the first one of said balance conditions, and means whereby the numerical position assumed by the pointer with relation to the scale to bring about the second one of said balance conditions will be a function in a power of ten of the resistance in ohms from the bridge X-faulty post out to the fault on the faulty conductor of the loop under test.

13. In a Wheatstone bridge for executing a Varley loop test, a handle and rigidly connected pointer therefor for operating the rheostat constituting the adjustable arm of the bridge an X-faulty post at the outer end of said adjustable arm, a movable scale of the rheostat cooperative with the pointer, means for operating the movable scale by the handle, a source of testing current, a current indicator for denoting a balanced condition of the bridge and loop under test, a switch for changing the battery connection from the X-faulty post to ground so as to apply the battery through the ratio arms in branch over the loop to the point of fault, means responsive to the operation of the handle for bringing about said operation of the switch and for also bringing about two different balance conditions of the Varley loop test indicated by the indicator, means whereby the scale and also the switch will be operated only while the handle is operated to bring about the first one of said balance conditions, and means whereby the numerical position assumed by the pointer with relation to the scale to bring about the second one of said balance conditions will be an even numerical multiple of the resistance in ohms from the bridge out to the fault on the faulty conductor of the loop under test.

14. In a rheostat, a resistor, a circuit adapted for including said resistor, a wiper for making contact along the resistor so as to introduce resistance of said resistor into the circuit, a graduated scale for indicating the resistance included by the resistor through the agency of the wiper movement, a handle for operating said wiper, means for operating the scale by the handle coincident with operating the wiper, means for further operating the wiper by the handle in a second stage movement to introduce more resistance by the resistor without further operating the scale, and means whereby the graduations on said scale as defined by the final position of the wiper will numerically indicate the value of the resistance introduced by the resistor only by the second stage of the movement, last said means involving a circuit changing switch operated by the handle coincident with operating the scale.

15. In a Wheatstone bridge for executing a Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge out to the fault on the faulty conductor of the loop under test, last three means involving a structure consisting of a resistor for said rheostat, a first hollow shaft, a second shaft slidable within said first shaft, a wiper for said first shaft cooperative with said resistor for varying the effective resistance value of said resistor, a circuit closing switch for said rheostat operated by said second shaft, and a common handle for operating said shafts whereby the resistance value of said resistor may be varied at will and the said switch may be operated at will independent of each other.

16. In a Wheatstone bridge for executing a Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge out to the fault on the faulty conductor of the loop under test, last three means involving a structure consisting of a resistor for said rheostat, a first hollow shaft, a second shaft slidable within said first shaft, a wiper for said first shaft cooperative with said resistor, for varying the effective resistance value of said resistor, a circuit changing switch for said rheostat operated by said second shaft, and a common handle for operating said shafts whereby the resistance value of said resistor may be varied at will and the said switch may be operated at will independent of each other.

17. In a Wheatstone bridge for executing a

- Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge out to the fault on the faulty conductor of the loop under test, last three means involving a structure consisting of a resistor for said rheostat, a first hollow shaft, a second shaft slidable within said first shaft, a wiper for said first shaft cooperative with said resistor for varying the effective resistance value of said resistor, a circuit changing switch for said rheostat operated by said second shaft, a common handle for operating said shafts, and means for operating the handle in one manner for varying the resistance value of the resistor and in another manner for operating the switch.
18. In a Wheatstone bridge for executing a Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge out to the fault on the faulty conductor of the loop under test, last three means involving a structure consisting of a resistor for said rheostat, a first hollow shaft, a second shaft slidable within said first shaft, a wiper for said first shaft cooperative with said resistor for varying the effective resistance value of said resistor, a circuit changing switch for said rheostat operated by said second shaft, a common handle for operating said shafts, and means for operating the handle in one manner for varying the resistance value of the resistor and in another manner for operating the switch.
19. In a Wheatstone bridge for executing a Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge out to the fault on the faulty conductor of the loop under test, last three means involving a structure consisting of a resistor for said rheostat, a first hollow shaft, a second shaft slidable within said first shaft, a wiper for said first shaft cooperative with said resistor for varying the effective resistance value of said resistor, a circuit changing switch for said rheostat operated by said second shaft, a common handle for operating the shafts, means for operating the handle in one manner for varying the resistance value of the resistor and in another manner for operating the switch, means for operating the handle for varying the resistance value of the resistor by a rotary movement and for operating the switch by an endwise movement, and means for at will effecting both said movements simultaneously for simultaneously varying the said resistance value and operating said switch.
20. In a Wheatstone bridge for executing a Varley loop test, a handle for operating the rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge out to the fault on the faulty conductor of the loop under test, last three means involving a structure consisting of a resistor for said rheostat, a first hollow shaft, a second shaft slidable within said first shaft, a wiper for said first shaft cooperative with said resistor for varying the effective resistance value of said resistor, a circuit changing switch for said rheostat operated by said second shaft, a common handle for operating said shafts, and means for operating the handle in one manner for varying the resistance value of the resistor and in another manner for operating the switch, and means for operating the handle for varying the resistance value of the resistor by a rotary movement and for operating the switch by an endwise movement, and means for at will effecting both said movements simultaneously for simultaneously varying the said resistance value and operating said switch.

- sistor, a circuit changing switch for said rheostat cooperative with the end of said second shaft, and a common handle for operating said first shaft in a rotary direction to 5 alter the value of the resistor or to operate said second shaft endwise to operate the said switch.
21. In a Wheatstone bridge for executing a Varley loop test, a handle for operating the 10 rheostat constituting the adjustable arm of the bridge, a movable graduated scale of the rheostat, means for operating the movable scale by the handle, a current indicator for denoting a balanced condition of the bridge 15 and loop under test, means responsive to the handle for bringing about the two different balance conditions of the Varley loop test indicated by the indicator, means whereby the scale will be operated only while the handle 20 is operated to bring about the first one of said balance conditions, means whereby the position assumed by the handle with relation to the scale to bring about the second one of said balance conditions will be an even mul- 25 tiple of the resistance in ohms from the bridge out to the fault on the faulty conductor of the loop under test, last three means involving structure consisting of a resistor for said rheostat, a first hollow shaft, a second shaft 30 slidable within said first shaft, a wiper for said shaft cooperative with said resistor for varying the effective resistance value of said resistor, a circuit changing switch for said rheostat cooperative with the end of said sec- 35 ond shaft, a common handle for operating said first shaft in a rotary direction to alter the value of the resistor or to operate said second shaft endwise to operate the said switch, and means whereby said endwise 40 movement may be made without effecting said rotary movement.
22. In a Wheatstone bridge for executing a Varley loop test, a handle for operating the 45 rheostat constituting the adjustable arm of the bridge, a movable graduated scale of the rheostat, means for operating the movable scale by the handle, a current indicator for denoting a balanced condition of the bridge and loop under test, means responsive to the 50 handle for bringing about the two different balance conditions of the Varley loop test indicated by the indicator, means whereby the scale will be operated only while the handle is operated to bring about the first one of said 55 balance conditions, means whereby the position assumed by the handle with relation to the scale to bring about the second one of said balance conditions will be an even mul- 60 tiple of the resistance in ohms from the bridge out to the fault on the faulty conductor of the loop under test, last three means involving a structure consisting of a resistor for said rheostat, a first hollow shaft, a second shaft 65 slidable within said first shaft, a wiper for said first shaft cooperative with said re- 70 sistor for varying the effective resistance value of said resistor, a circuit changing switch for said rheostat cooperative with the end of said second shaft, a common handle for operating said first shaft in a rotary direc- 75 tion to alter the value of the resistor or to operate said second shaft endwise to operate the said switch, and means whereby said rotary movement may be made without effecting said endwise movement.
23. In a Wheatstone bridge for executing a Varley loop test, a handle for operating the 80 rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different 85 balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge 90 out to the fault on the faulty conductor of the loop under test, last three means involving a structure consisting of a resistor for said rheostat, a first hollow shaft, a sec- 95 ond shaft slidable within said first shaft, a wiper for said first shaft cooperative with said resistor for varying the effective resist- 100 ance value of said resistor, a circuit changing switch for said rheostat cooperative with the end of said second shaft, a common handle for operating said first shaft in a rotary di- 105 rection to alter the value of the resistor or to operate said second shaft endwise to operate the said switch, and means whereby both said movements may be made simultaneously to simultaneously operate the wiper to vary the effective value of the resistor and to operate the switch.
24. In a Wheatstone bridge for executing a Varley loop test, a handle for operating the 110 rheostat constituting the adjustable arm of the bridge, a movable graduated scale of the rheostat, means for operating the movable scale by the handle, a current indicator for denoting a balanced condition of the bridge and loop under test, means responsive to the handle for bringing about the two different 115 balance conditions of the Varley loop test indicated by the indicator, means whereby the scale will be operated only while the handle is operated to bring about the first one of said balance conditions, means whereby the position assumed by the handle with relation to the scale to bring about the second one of said balance conditions will be an even multiple of the resistance in ohms from the bridge 120 out to the fault on the faulty conductor of the loop under test, last three means involving a structure consisting of a resistor for said rheostat, a first hollow shaft, a second shaft 125 slidable within said first shaft, a wiper for said first shaft cooperative with said re- 130 sistor for varying the effective resistance value of said resistor, a circuit changing switch for said rheostat cooperative with the end of said second shaft, a common handle for operating said first shaft in a rotary direc-

loop under test, last three means involving a structure consisting of a resistor for said rheostat, a shaft, a wiper on said shaft for modifying the effective resistance of the resistor, a scale corresponding to said resistor, a pointer cooperative with said scale rigidly connected with said wiper through the shaft to indicate the effective resistance value included by said resistor, and means for moving said scale by 5 said shaft while moving said wiper over only certain portions of the resistor so that the pointer will indicate the value of the effective resistance included by the resistor modified in a predetermined manner from that actually 10 included.

25. In a Wheatstone bridge for executing a Varley loop test, a handle for operating the rheostat constituting the adjustable arm of the bridge, a movable graduated scale of the 20 rheostat, means for operating the movable scale by the handle, a current indicator for denoting a balanced condition of the bridge and loop under test, means responsive to the handle for bringing about the two different 25 balance conditions of the Varley loop test indicated by the indicator, means whereby the scale will be operated only while the handle is operated to bring about the first one of said balance conditions, means whereby the position 30 assumed by the handle with relation to the scale to bring about the second one of said balance conditions will be an even multiple of the resistance in ohms from the bridge out to the fault on the faulty conductor of the 35 loop under test, last three means involving a structure consisting of a resistor for said rheostat, a shaft, a wiper on said shaft operated for modifying the effective resistance of the resistor, a pointer rigidly moved with the 40 shaft and wiper, a scale cooperative with said pointer for indicating the position of said wiper, a handle, an auxiliary circuit changing switch, and means for differently operating said handle for at will effectively operating 45 only the wiper or at will operating only the switch.

In witness whereof, I hereunto subscribe my name this eighth day of July, 1926.

HERBERT M. FRIENDLY.
